UNITED STATES PATENT OFFICE

150,635

DESIGN FOR A COSMETIC APPLICATOR

Mary Stevens Landsman, Chicago, Ill.

Application October 29, 1947, Serial No. 142,198

Term of patent 7 years

(Cl. D86—10)

To all whom it may concern:

Be it known that I, Mary Stevens Landsman, a citizen of the United States, residing at Chicago, in the county of Cook and State of Illinois, have invented a new, original, and ornamental Design for Cosmetic Applicator, of which the following is a specification, reference being had to the accompanying drawing, forming a part thereof.

In the drawing:

I claim:

The ornamental design for a cosmetic applicator, substantially as shown.

MARY STEVENS LANDSMAN.
